New York, N.Y. 10028

Filed July 17, 1967, Ser. No. 7,831

Term of patent 3½ years

(Cl. D42—8)

FIG. 1 is a front elevational view of a combined wristwatch and locket showing my new design;

FIG. 2 is a top plan view thereof;

FIG. 3 is a front elevational view, in open condition;

FIG. 4 is a side elevational view taken from the right of FIG. 1; and

FIG. 5 is a rear elevational view thereof.

The essential features of the design are shown in full lines.

I claim:

The ornamental design for a combined wristwatch and locket, substantially as shown, and described.
